UNITED STATES PATENT OFFICE.

LUDWIG DÜRR, OF BODENSEE, GERMANY, ASSIGNOR TO LUFTSCHIFFBAU ZEPPELIN GESELLSCHAFT MIT BESCHRÄNKTER HAFTUNG, OF FRIEDRICHSHAFEN, BODENSEE, GERMANY.

FIN AND RUDDER OF AIRSHIPS.

Application filed November 12, 1925, Serial No. 68,488, and in Germany November 29, 1924.

My invention relates to fins and rudders of airships.

It has become usual to arrange the fins cross-wise at the stern of the ship and to place the rudders and elevators behind the fins so that in their middle position the surfaces of rudders and elevators form continuations of the corresponding fin surfaces. Thus there are usually two vertical rudders, one above and one below the rear hull portion. Generally these rudders are operated together, each when turned at an angle causing a cross pressure on the ship's stern.

Because of the ship having cars situated underneath its hull or body the lower rudder will have less efficiency than the upper one, both having the same surface and usually the same shape. This causes a very undesirable effect on the ship's horizontal course, as the resistance from the rudder above the hull or body will differ from the resistance of the lower rudder, and this will have a rolling effect on the ship as a whole.

According to my invention I am doing away with these drawbacks by horizontally extending the surface of the lower rudder, so that it is wider than the upper one. Furthermore it may be advisable to also increase the area of the lower rudder by an adequate change in its shape. Also in accordance with my invention it may be useful to provide means for always giving the lower rudder a wider angle of deviation than the upper rudder has at the same time.

This for example may be attained by making the operating levers of the lower rudder shorter than those of the upper rudder while the control wires of both rudders are moved over equal distances.

Having given a general description of my invention I now want to point it out more in detail referring to the drawings giving an example embodying my invention.

Fig. 1 is a side elevation of an airship, partly broken up, showing only the bow and the stern portions.

Fig. 2 is the corresponding top view represented in like manner as Fig. 1.

Body or hull 1 in the stern has horizontal fins 2 with elevators 3 and vertical fins 4 with rudders 5 and 6. Underneath the bow a control car 7 is situated. From the

upper rudder 5 control wires 8 are running to the gear 9, situated in or above control cabin 7 in which there is the hand wheel 13. Lower rudder 6 is connected to the same operating mechanism 9 by means of control wires 10. These wires 10 operate rudder 6 by turning the short-legged lever 11 which is in rigid connection with rudder 6. Rudder 5 is rigidly connected with long-legged lever 12 which is turned by wires 8. Thus for example one turn of hand wheel 13 will cause a wider angle of deviation with lower rudder 6 than with upper rudder 5.

I do not want to limit myself to the example described or shown in the drawings as many variations will occur to those skilled in the art.

What I claim is:

1. A lighter than air airship comprising a gas inflated hull; a substantially vertical rudder situated above said hull; and a substantially vertical rudder situated below said hull; said lower rudder having a longer horizontal extension than said upper rudder.

2. A lighter than air airship comprising a gas inflated hull; an upper and a lower vertical fin at the stern of said hull; two rudders, each forming the continuation of one of said fins, respectively, the lower one of said rudders having a larger area than said upper rudder.

3. A lighter than air airship comprising a gas inflated hull; a rudder situated above said hull; a rudder situated below said hull; and means for operating said two rudders; said means being adapted at the same time to cause said lower rudder to have a wider angle of deviation than said upper rudder.

4. An airship comprising a gas inflated hull; a substantially vertical rudder situated above said hull; and a substantially vertical rudder situated below said hull; said lower rudder having both a longer horizontal extension and a larger area than said upper rudder.

5. An airship comprising a gas inflated hull; a rudder situated above said hull; a rudder situated below said hull; said lower rudder having a longer horizontal extension than said upper rudder; and means for operating said two rudders; said means being

adapted at the same time to cause said lower rudder to have a wider angle of deviation than said upper rudder.

6. A lighter than air airship comprising
5 a gas inflated hull; a rudder situated above
said hull; a rudder situated below said hull;
said lower rudder having a larger area than

said upper rudder; and means for operating
said two rudders; said means being adapted
at the same time to cause said lower rudder 10
to have a wider angle of deviation than said
upper rudder.

DR. LUDWIG DÜRR.
